US0D1079704S

(12) **United States Design Patent** (10) **Patent No.:** **US D1,079,704 S**
(45) **Date of Patent:** **** Jun. 17, 2025**

(54) **DATA CAPTURE DEVICE**

(71) Applicant: **ZEBRA TECHNOLOGIES CORPORATION**, Lincolnshire, IL (US)

(72) Inventor: **Steven D. Sieckowski**, Port Jefferson, NY (US)

(73) Assignee: **Zebra Technologies Corporation**, Lincolnshire, IL (US)

(**) Term: **15 Years**

(21) Appl. No.: **29/738,815**

(22) Filed: **Jun. 19, 2020**

(51) **LOC (15) Cl.** **14-02**

(52) **U.S. Cl.**

USPC **D14/420**

(58) **Field of Classification Search**

(57) **CLAIM**

The ornamental design for a data capture device as shown and described.

DESCRIPTION

FIG. 1 is a first perspective view of a data capture device; FIG. 2 is a second perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines showing portions of the data capture device form no part of the design claimed.

1 Claim, 8 Drawing Sheets
